SPIRAL BINDER

Sumner W. Dow, Boston, Mass.

Application August 8, 1938, Serial No. 223,748

4 Claims. (Cl. 281—19)

This invention relates to certain new and useful improvements in spiral binders.

The primary object of the invention is to provide a spiral binder especially designed for check book use wherein a pack of at least five hundred checks may be conveniently supported within a backing or book cover.

A further object of the invention is to provide a spiral binder of the foregoing character wherein in the back of the cover has a pair of mating plates substantially semi-circular in cross-section to provide a rounded surface at the back of the cover with the plates connected together and to the fabric of the back of the cover and provided with means for the detachable connection of the spiral binder which carries the leaves of the book.

With the above and other objects in view that will become apparent as the nature of the invention is better understood, the same consists in the novel form, combination and arrangement of parts hereinafter more fully described, shown in the accompanying drawings and claimed.

25 In the drawings:

Figure 1 is a fragmentary end elevational view of a book of the check book type equipped with the spiral binder of the present invention;

Figure 2 is a fragmentary end elevational view, similar to Figure 1, with the top cover of the book broken away and a convolution of the spiral binder visible;

Figure 3 is a fragmentary top plan view with the top cover in open position illustrating the spiral binder, with a part of the attaching means for securing the spiral binder to the book back;

Figure 4 is a detail fragmentary sectional view showing a finger struck-out from an arcuate plate of the book backing for retaining engagement with several convolutions of the spiral binder;

Figure 5 is a detail fragmentary sectional view showing struck-out V-shaped ribs of an arcuate plate of the backing constituting guides for centering the spiral binder and arresting longitudinal movement of the spiral binder;

Figure 6 is an inner face view of the book binding with the covers in opened position, fragmentarily illustrated and the spiral binder removed to illustrate the devices to which the spiral binder is attached;

Figure 7 is a longitudinal sectional view of the book backing showing the metallic backing element and the fabric strip associated therewith connected together;

55 Figure 8 is a longitudinal sectional view, simi-

lar to Figure 7, with the spiral binder and the book leaves carried thereby moved to an arched position to facilitate engagement of the convolutions of the spiral binder with the holding means therefor carried by the book backing; and

Figure 9 is a detail sectional view showing another construction for connecting together the arcuate metal plates of the book backing.

The invention in this case primarily resides in the construction of the book backing for the support of a spiral binder, the latter being of the usual construction and comprising a coiled wire 15 having the convolutions thereof widely spaced apart as is common in such devices with the convolutions threaded through a stack of book leaves 16, preferably bank checks.

The book backing designated in general by the reference character 17 carries top and bottom covers 18 and 19 for the book leaves 16 with the top and bottom covers 18 and 19 flexibly hinged in the zones 20 to the backing 17.

As shown in Figs. 1 to 8, the book backing 17 includes a pair of elongated metal plates 21 and 22, substantially semi-circular in cross-section and nested together, a leather or fabric sheet 23 overlying the plate 22 while a leather or fabric sheet 24 is interposed between the plates 21 and 22, these leather or fabric sheets being extended as at 23a and 24a shown in Figs. 4 and 5 to provide the top and bottom covers 18 and 19 of the book as well as provide the hinge connections 20 between the top and bottom covers 18 and 19 and a backing 17. The backing 17 comprising the elongated arcuate metallic plates 21 and 22 and the fabric sheets 23 and 24 has said parts secured together as by an adhesive or the like and additionally anchored in assembled relation by means of rivets 25 shown in Figs. 6 to 8.

To facilitate attachment of the spiral binder 40 to the book backing, a relatively long inwardly directed finger 26 is struck-up from each end of the plate 21. An intermediate relatively shorter finger 27 is struck-up from the plate 21 intermediate the ends thereof and may point 45 toward either end of said plate. Devices are carried by the plate 21 to be positioned between the convolutions of the coil binder for restraining the latter against longitudinal movement within the book binding and for holding the end 50 convolutions engaged with the fingers 26, said devices being arranged in groups at each side of the intermediate finger 27 and comprising V-shaped ribs 28 struck-up from the plate 21.

To place the spiral binder and the book leaves 55

carried thereby in engagement with the backing 17, the spiral binder with the book leaves are arched as illustrated in Figure 8, to place each end convolution of the spiral binder in position for engagement with the adjacent end finger 26 and upon flattening movement of the spiral binder and book leaves, several of the end convolutions are engaged with the end fingers 26 as shown in Figure 3. The V-shaped ribs 28 are respectively positioned between adjacent convolutions of the coil binder 15 as shown in Figure 5 and by manipulation of the spiral binder intermediate its ends, one of the convolutions thereof is engaged with the intermediate struck-up finger 27. Each end of the metal plate 21 of the backing 17 carries a substantially circular wall 29 extending at right angles to the longitudinal axis of the backing to overlie the end of the coil binder and adjacent ends of the leaves 16, as illustrated on the drawings and give a finished appearance to the book as shown in Figs. 1 and 2. The metallic plate 22 acts as a reinforcing element for the plate 21 in the backing 17 to which latter plate the spiral binding with the book leaves is attached, the arcuate formation of the metal plates 21 and 22 in cross-section presenting a rounded face to the backing 17 to give a more graceful appearance thereto. When the spiral binding or backing is used in a bank 30 check book construction and all of the checks have been used, the spiral backing may be permanently anchored in the spiral binding and said stubs may be permanently anchored in the backing by flattening or bending the intermediate finger 27 into permanent engagement within the associated convolution of the spiral binder.

In the form of invention shown in Fig. 9, the rivets 25 that tighten the several elements of the backing 17 are eliminated and in view thereof 40 an angular finger 25a is struck-out from the arcuate backing plate 22 and passes through an opening 21a in the arcuate plate 21 for securing the plates 21 and 22 together.

From the above detailed description of the invention, it is believed that the construction and 45 operation thereof will at once be apparent and while there are herein shown and described the preferred embodiments of the invention, it is nevertheless to be understood that minor changes 50 may be made therein without departing from the spirit and scope of the invention as claimed.

I claim:

1. In a book backing and spiral binder, a backing comprising a pair of metallic plates and alternate fabric layer connected together, said metallic plates being arcuate in cross-section with the inner metallic plate exposed, the spiral binder including a wire coil carrying a book of leaves, top and bottom covers carried by the backing and 55 separate means carried by the exposed plate for securing the spiral binder to the backing and prevent longitudinal movements of the spiral binder relative to the backing, said means including end fingers struck-up from the exposed plate and directed towards each other for detachable engagement with the adjacent end convolutions of the spiral binder, and groups of V-shaped ribs struck-up from the exposed plate inwardly of said fingers with the ribs of each group respectively positioned between adjacent 60 convolutions of the spiral coil.

2. In a book backing and spiral binder, a back-

ing comprising a pair of metallic plates and alternate fabric layer connected together, said metallic plates being arcuate in cross-section with the inner metallic plate exposed, the spiral binder including a wire coil carrying a book of leaves, 5 top and bottom covers carried by the backing and separate means carried by the exposed plate for securing the spiral binder to the backing and prevent longitudinal movements of the spiral binder relative to the backing, and one of said means adapted to be manipulated for permanently securing the spiral binder to the backing, said means including end fingers struck-up from the exposed plate and directed towards each other for detachable engagement with the adjacent end convolutions of the spiral binder, and groups of V-shaped ribs struck-up from the exposed plate inwardly of said fingers with the ribs of each group respectively positioned between adjacent 10 convolutions of the spiral coil.

3. In a book backing and spiral binder, a backing comprising a pair of metallic plates and alternate fabric layer connected together, said metallic plates being arcuate in cross-section with the inner metallic plate exposed, the spiral binder including a wire coil carrying a book of leaves, 15 top and bottom covers carried by the backing and separate means carried by the exposed plate for securing the spiral binder to the backing and prevent longitudinal movements of the spiral binder relative to the backing, said means including end fingers struck-up from the exposed plate and directed towards each other for detachable engagement with the adjacent end convolutions of the spiral binder, and groups of V-shaped ribs struck-up from the exposed plate inwardly of said fingers with the ribs of each group respectively positioned between adjacent 20 convolutions of the spiral coil.

4. In a book backing and spiral binder, a backing comprising a pair of metallic plates and alternate fabric layer connected together, said metallic plates being arcuate in cross-section with the inner metallic plate exposed, the spiral binder including a wire coil carrying a book of leaves, 25 top and bottom covers carried by the backing and separate means carried by the exposed plate for securing the spiral binder to the backing and prevent longitudinal movements of the spiral binder relative to the backing, said means including end fingers struck-up from the exposed plate and directed towards each other for detachable engagement with the adjacent end convolutions of the spiral binder, and groups of V-shaped ribs struck-up from the exposed plate inwardly of said fingers with the ribs of each group respectively positioned between adjacent 30 convolutions of the spiral coil, and a flat disk plate carried by each end of the exposed plate and extending at right angles therefrom toward the concaved side of said plate to overlie the adjacent end of the spiral binder and adjacent ends of the book of leaves.

4. In a book backing and spiral binder, a backing comprising a pair of metallic plates and alternate fabric layer connected together, said metallic plates being arcuate in cross-section with the inner metallic plate exposed, the spiral binder including a wire coil carrying a book of leaves, 35 top and bottom covers carried by the backing and separate means carried by the exposed plate for securing the spiral binder to the backing and prevent longitudinal movements of the spiral binder relative to the backing, said means including end fingers struck-up from the exposed plate and directed towards each other for detachable engagement with the adjacent end convolutions of the spiral binder, and groups of V-shaped ribs struck-up from the exposed plate inwardly of said fingers with the ribs of each group respectively positioned between adjacent 40 convolutions of the spiral coil, and a flat disk plate carried by each end of the exposed plate and extending at right angles therefrom toward the concaved side of said plate to overlie the adjacent end of the spiral binder and adjacent ends of the book of leaves.
